SHEET MAGAZINE FOR PRINTING PRESSES

Abel Kluge and Eneval Kluge, St. Paul, Minn., assignors to Brandtjen and Kluge, Inc., St. Paul, Minn., a corporation of Minnesota

Application March 27, 1933, Serial No. 662,892

14 Claims. (Cl. 271—61)

Our invention relates to sheet magazines for printing presses of the same general character as the stock magazine disclosed in Patent No. 1,694,015 of December 4, 1928 which eventuated from an application filed by us.

In our previously patented device, as in the present case, the magazine is pivotally mounted at one end thereof at one side of a printing press and is swingable horizontally from closed, operative position transversely of the press at the front thereof to an open, inoperative position along the side of the press where it is out of the way of the pressman during make ready.

Our present invention has for an object there- 15 of to provide improved means for supporting the free end of the swingable magazine in its closed, operative position and for releasably securing the magazine in such position.

Another object of the invention is to provide 20 improved means for transmitting motion to the sheet advancing mechanism of the magazine.

More specifically it is an object of our invention to supply for the free end of the swingable magazine a self-latching support having latching 25 means for accurately disposing the magazine in its closed, operative position and which supplies a medium providing for the continued support for the free end of the magazine when it is swung open from its said operative position.

Another object of the invention is to provide 30 for the free end of a swingable magazine self-latching supporting means capable of adjustment to accommodate the magazine in different operative positions thereof and having cooperat- 35 ing latching elements which remain relatively undisturbed in various adjustments of said sup- porting means.

A further object of the invention is to provide 40 a magazine latching device of the present character including a spring which operates to hold the magazine relative to the supporting press frame and with such firmness as to prevent vibration and the rattling of parts.

An additional object of the invention is to pro- 45 vide in the driving train for operating the sheet advancing mechanism of the magazine a swivel- ing connection wherein the post, on which the magazine swings, is embodied as an element.

With the foregoing and other objects in view, 50 which will appear in the following description, the invention resides in the novel combination and arrangement of parts and in the details of construction hereinafter described and claimed.

In the drawing, Fig. 1 is a perspective view of 55 a swingable sheet magazine embodying our in-

vention, the same being shown in connection with a platen press of the familiar Gordon type—Fig. 2 and Fig. 3 are vertical sectional views showing in detail the construction of the support at the free end of the magazine and illustrating particularly the latching mechanism for said support, and Fig. 4 is a vertical sectional view in detail illustrating the swiveling connection in the driving train which operates the sheet advancing mechanism of the magazine. 5

Referring to the drawing, the illustrated press parts, which will be recognized at once include the usual side frame brackets 10 and gear guard 11. The platen, designated by the numeral 12, is shown in its open position. The crank disk 13 and the front shaft 14 on which said disk is mounted are shown together with a portion of the side arm 15 and a portion of the roller frame link 16 at one side of the press. 10

The sheet magazine portrayed includes an in- 20 clined bed plate 17 for supporting a pack of sheets on edge, said plate having end frames 18 thereon in which is slidably guided an inclined back rest 19 for such sheets.

A supporting post 20 for the magazine is 25 swiveling socketed in a bore 21 in a boss 22 on the gear guard 11 and is held at different elevations by means of a rest in the form of a collar 23 which bears on said boss, said collar being adjust- 30 ably secured to said post by means of a set screw 24 threaded in the collar. A horizontal support- 35 ing arm 25 carried by the post 20 is horizontally and angularly adjustable thereon, a reduced end 25^a of said arm, circular in cross section, being inserted in a transverse bore 26 in said post 20, 40 the adjustment of the arm 25 with respect to the post 20 being maintained by means of a set screw 27 threaded in the post and adapted to be turned against said reduced end 25^a of said arm. The bed plate 17 of the magazine proper is trunnioned 45 on the supporting arm 25, a boss 28 being formed at one end of said bed plate and inserted in a transverse bore 29 in said arm, the boss 28 nor- 50 mally being held against turning in said arm by means of a set screw (not shown) threaded in the arm and turned against said boss. Swing- 55 ably mounted, as above indicated, on the swivel- ing post 20, the magazine proper may be swung forth and back into and out of operative relation across the front of the press (Fig. 1) and may be adjusted to secure the desired accurate disposi- 60 tion thereof, in its operative relation, through an adjustment of the post 20 in the gear guard 22 and/or an adjustment of the arm 25 relative to the post 20 and/or an adjustment of the boss 28 65

relative to said arm 25, such of said adjustments as may be necessary being made to bring the bed plate 17 of the closed magazine and particularly the upper edge thereof into proper relation with respect to the path of the sheet feeding mechanism employed in taking sheets from the magazine to the platen of the press.

At the free end of the magazine is a support consisting of a leg 30 depending from the bed plate 17, said leg being formed with a hollow foot 31 having a toe 32 and heel 33. Inserted through vertical slots 34 cut in opposite walls of the hollow foot 31 is a latch lever 35, said lever being pivoted to said foot by means of a horizontally disposed pintle 36. A socket 37 consisting of an axial bore in the lower portion of the leg 30 receives and holds an expansion spring 38 which bears at its lower end against the upper edge of the latch lever 35 at the rear of the pintle 36. Said lever 35, unless otherwise positioned against the action of said spring 38, is caused by said spring to bear against the limit stop 39 (Fig. 2), at the bottom of the rear slot 34 in the shoe 31. The forward end of the latch lever 35 projects through the front slot 34 in the shoe and at its tip has a beveled cam surface 40 extending rearwardly from the lower edge of the lever to the upper edge thereof. Cut in the latch lever 35 immediately at the rear of the cam surface 40 is a V-shaped notch 41 which cooperates with a latch pin 42. This pin 42, occupying a horizontal position, is mounted at one end thereof in an upright ear 43 formed integrally with an elongated latch block *a*, said block being a hollow structure consisting of a side wall 44 having an integral top flange 45, bottom flange 46 and end flanges 47. Slots 48 (Fig. 3), formed in the bottom flange 46 of the block *a* and extending lengthwise of said block, receive threaded anchoring studs 49 which are threaded in the frame bracket 10 at the side of the press opposite the gear guard 11. Bearing nuts 50 on said studs 49 engage the underside of the lower flange 46 and lock nuts 51 on said studs engage the upper side of said lower flange.

When the magazine is latched closed in its operative position (Fig. 1), the latch lever 35 is disposed as shown in Fig. 3 with the tapered sides of the notch 41 in said lever engaging the latch pin 42. To swing the magazine away from its operative position, the pressman grasps the angularly disposed handle 52 at the rear end of the lever 35 and lifts upwardly thereon swinging said lever out of engagement with the latch pin 42 and into the position shown in dotted lines in Fig. 2, wherein the lower edge of the forward end of said lever bears against the limit stop 53 at the bottom of the front slot 34 in the shoe 31. In thus disengaging the latch lever 35 from the pin 42 an appreciable lifting force is transmitted through the spring 38 to the magazine proper, such force to a considerable extent counterbalancing the weight of the magazine and its contents. Having a convenient grip upon the lever 52, the pressman swings the magazine open and at the same time readily continues to exert a lifting force on said lever with the result that the magazine and its swinging mounting are not subjected to undue strains. The magazine is closed in the same manner and with the same effect as in the opening thereof. After the shoe 31 has swung into place on the latch block *a* in final stage of the closing throw of the magazine, the pressman releases latch lever 35 which is then acted upon by the spring 38, said lever thereupon re-engaging the pin 42, the tapered sides of the

notch 41 acting as opposed cams and serving to position the magazine accurately in its operative position.

The adjustability of the nuts 50 on the anchoring studs 49 provides for a variation of adjustments of the latch block *a* to accord with the adjustment of the magazine proper on the post 20. The longitudinal adjustment of the latch block *a*, attained by moving the block forward or backward relative to the anchoring studs 49, determines the horizontal angular relation of the magazine with respect to the press in the latched position of the magazine. To accord with the vertical angularity of the magazine longitudinally thereof the latch block *a* is raised or lowered on the anchoring studs 49 and to accord with the angularity of said magazine laterally thereof, one end of the block is set at a different elevation than the other. In any event the latch block *a* is stationed so that the bottom of the shoe 31 will skirt the upper surface of said block when the magazine is swung into its closed position. With this relation obtaining between the block *a* and shoe 31, any forward or backward adjustment of the block will leave the latch lever 35 and latch pin 42 in proper cooperative relation.

After the magazine is fully closed and the latch lever 35 released, in latching position, the spring 38, acting through said lever 35 and the pin 42, firmly holds the shoe 31 in place upon the block *a*. If the pressman should close the magazine merely by pushing it and without lending any support to the magazine through the handle of latch lever 35, the cam surface 40 at the tip of said lever will engage beneath the pin 42 and automatically tilt the lever 35 so that the notch 41 therein will catch said pin.

Included in the magazine structure is a winding shaft 54 having drums 55 thereon. Tapes 56 fastened to the back rest 19 are wound upon said drums 55 when the shaft 54 is turned. A rocker-disk 56 having a ratcheting connection (not shown) with the shaft 54 turns said shaft step-by-step to advance the back rest 19. The mechanism for rocking the disk 56, as in the disclosure in our said Patent No. 1,694,015, includes an upright reciprocating rod 57 (Fig. 4). This rod 57 has a novel swiveling connection with the rocker disk 56 which compensates for the swinging movements of the magazine, thus avoiding any necessity of disconnecting said mechanism before the magazine is swung out of its operative position and again connecting the mechanism after the magazine is returned to its operative position. Said swiveling connection is constructed with the post 20 as an element thereof, the details of said connection being best seen in Fig. 4. A collar 58 on the post 20, is connected with the reciprocating rod 57 and is moved up and down on said post by the rod, rotational movement of said collar being prevented by said rod. This collar 58 has a reduced sleeve-like portion 59, an annular shoulder or rest 60 being provided on said collar. A second collar 61, journaled on said reduced portion 59 of said first collar, is confined on the first collar between the shoulder 60 and a retaining ring 62, said ring being secured on said reduced collar portion 59 by means of set screws 63. A link 64 connects said second collar 61 with the rocker-disk 56 and serves to rock said disk 56 when the said collar assembly is raised and lowered on the post 20 by the action of the rod 57. Upon swinging the magazine, the link 64 causes the collar 61 to turn upon the collar 58, this being the only effect of such movement of the maga-

zine on the driving train between the rod 57 and rocker-disk 56. Thus, it will be seen that the driving connection in so far as the operation thereof is concerned, remains unaffected in any position that may be occupied by the swingable magazine.

Changes in the specific form of our invention, as herein disclosed, may be made within the scope of what is claimed without departing from the spirit of our invention.

Having described our invention, what we claim as new and desire to protect by Letters Patent is.

We claim:

1. In a device of the character described, a post mounted to turn on its own axis, a bed-plate for sheets mounted at one end thereof on said post, a supporting leg for said bed-plate depending therefrom at its end opposite said post, said leg being formed with a shoe having a slot therethrough, a latch lever disposed in said slot and pivoted to said shoe, the ends of said lever projecting from said shoe, one of the projecting ends of said lever having a notch formed therein, a latch block providing a rest for the shoe in one of the positions in which said bed-plate may be swung, a latch pin mounted on the latch block and adapted to be caught in the notch in said latch lever, the projecting end of said lever opposite said notched end thereof serving as a hand hold for releasing the latch lever from the latch pin and as a medium for swinging the bed-plate and counterbalancing the weight thereof and of its contents in positions of said bed-plate in which it is unsupported by said latch block.

2. In a device of the character described, a structure for receiving a pack of sheets, means for swingably supporting said structure, a leg depending from said structure, a rest for said leg, cooperating latching members for holding said structure against swinging from a given position thereof in which said leg stands upon said rest, one member being carried by the leg and another by said rest, and a spring serving to actuate one of said members and also to yieldingly hold said leg upon said rest.

3. A sheet magazine having a movable back rest for advancing sheets and having a rocker-member for moving said back rest, a post mounted to turn on its own axis and swingably supporting said magazine, a collar mounted on said post, a second collar mounted to turn on said first collar but deprived of axial movement with respect thereto, a reciprocating rod for imparting movement to said first collar axially of the post, and a link connecting said second collar with said rocker-member.

4. A sheet magazine having a movable back rest for advancing sheets and having a rocker-member for moving said back rest, a post mounted to turn on its own axis and swingably supporting said magazine, a reciprocating rod, a link connected with said rocker-member, and a swiveling connection between said rod and link, the axis of said connection being coincident with the axis of said post.

5. A sheet magazine having a movable support for advancing a pack of sheets, said magazine being mounted to swing about an axis, and reciprocating members cooperating to move said support, said members having a swiveling connection between them, the axis of said connection coinciding with the axis about which said magazine swings.

6. A sheet magazine swingably mounted at one portion thereof and having a support at another

portion thereof, a rest for said support, cooperating latching members for holding said magazine against swinging from a given position thereof in which said support bears upon said rest, one latching member being mounted on the rest and the other on said support, the latter member including a hand hold for releasing said member from the other latching member and for swinging the magazine and counterbalancing the weight thereof.

7. In a device of the character described, a structure for receiving a pack of sheets, means swingably supporting said structure, a leg depending from said structure, a rest for said leg, cooperating latching members for holding said structure against swinging from a given position thereof in which said leg stands upon said rest, one member being carried by the leg and another by said rest, and a spring carried by said leg, said spring serving to actuate the latching member on the leg and also to yieldingly hold the leg upon said rest.

8. In a device of the character described, a structure for receiving a pack of sheets, means swingably supporting said structure, a leg depending from said structure, a rest for said leg, cooperating latching members for holding said structure against swinging from a given position thereof in which said leg stands upon said rest, one member being carried by the leg and another by said rest, said leg having a socket therein, a compression spring housed within said socket and acting against the latching member on the leg, said spring serving to actuate said member and to cause the leg to be pressed against said rest.

9. In a device of the character described, a frame, a structure for receiving a pack of sheets, means swingably supporting said structure on said frame at different elevations, a leg depending from said structure, a latch block mounted on the frame and providing a rest for said leg, said latch block being vertically adjustable on said frame to accord with the vertical adjustment of said sheet receiving structure, and cooperating latching members for holding said structure against swinging from a given position thereof in which said leg stands upon said latch block, one member being carried by the leg and another by said adjustable latch block.

10. A sheet magazine swingably mounted at one portion thereof and having a support at another portion thereof, a rest for said support, cooperating latching members, one carried by said support and the other mounted on said rest, and yielding means acting upon one of said latching members to hold it in engagement with the other latching member and serving further, through both of said latching members in their latched relation, to hold said leg firmly upon said rest.

11. In a device of the character described, a frame, a structure for receiving a pack of sheets, a support on said frame, said structure being swingably mounted thereon and tiltingly adjustable longitudinally, a leg depending from said structure, a latch block mounted on the frame and providing a rest for said leg, cooperating latching members for holding said structure against swinging from a given position thereof in which said leg stands upon said latch block, one member being carried by the leg and another by said latch block, said latch block being adjustable vertically to accord with the adjustment of said sheet receiving structure.

12. In a device of the character described, a frame, a structure for receiving a pack of sheets, a support on said frame, said structure being swingably mounted thereon and tiltingly adjustable laterally, a leg depending from said structure and having a shoe extending laterally relative to said structure, a latch block mounted on the frame and providing a rest for said leg, cooperating latching members for holding said structure against swinging from a given position thereof in which said shoe bears upon said latch block, one member being carried by the leg and another by said latch block, said latch block being tiltingly adjustable to accord with the positions occupied by said shoe in the various adjustments of said sheet receiving structure.
13. In a device of the character described, a structure for receiving a pack of sheets, means
- 5
- supporting said structure for movement into and out of a number of operative positions including positions varying in elevation, and self-latching means for locking said structure in any operative position into which it may be moved.
14. In a device of the character described, a frame, a structure for receiving a pack of sheets, means on the frame supporting said structure thereon for movement into and out of a number of operative positions, and self-latching means 10 for locking the structure in any selected operative position, said means including cooperating latching members, one carried by said structure and another mounted on said frame and adjustable thereon to accord with the selected operative 15 position of said structure.
